UNITED STATES PATENT OFFICE

ERNEST CORREALE AND GIOVANNI CORREALE, OF WEST HOBOKEN, NEW JERSEY.

BILLIARD TABLE.

Application filed July 11, 1923. Serial No. 650,884.

To all whom it may concern:

Be it known that we, ERNEST CORREALE, a citizen of the United States of America, and GIOVANNI CORREALE, a subject of Italy, both residing at #423 De Mott Street, in the town of West Hoboken, in the county of Hudson and State of New Jersey, have invented new and useful Improvements in Billiard Tables, of which the following is a specification.

This invention relates to improvements in billiard tables and has for an object the provision of means for securing the cushions in position, whereby a uniform height of the said cushions above the table bed may be maintained.

Another object of the invention is the provision of a pocket billiard table wherein the balls will be returned to one end of the table after entering the pockets, the returning means being of a character which will prevent the balls from sticking during their return journey.

Another object of the invention is the provision of means included in the returning means for preventing damage to the balls, the said means also acting to eliminate noise due to the balls rolling along a runway or subway beneath the table.

Another object of the invention is the provision of means for returning the balls to a position for their convenient removal without the use of the usual box and without any projecting surfaces to become damaged or interfere with the comfort of players.

With the above and other objects in view, the invention further includes the following novel features and details of construction, to be hereinafter more fully described, illustrated in the accompanying drawings and pointed out in the appended claims.

In the drawings:

Figure 1 is a top plan view partly broken away and showing the billiard table constructed in accordance with the invention.

Figure 2 is an end view of the same.

Figure 3 is a top plan view partly broken away with the bed, rails and cushions removed.

Figures 4 and 5 are enlarged fragmentary sections taken respectively on the lines 4—4 and 5—5 of Figure 1.

Referring to the drawings in detail where like characters of reference denote corresponding parts, the table which constitutes

the present invention comprises a frame 10 which is mounted upon suitable supporting legs 11 and which in turn supports a bed or slate 12, the latter being covered with the usual cloth 13. Mounted upon the bed 12 are side and end rails 14, while secured to the latter are the usual rubber or resilient cushions 15, the cushions and rails 14 being also covered with a cloth 16. A trim of any character such as is indicated at 17 may be provided around the sides and ends of the table.

In the usual construction of billiard tables, the rails which carry the cushions are bolted to the facing or trim by horizontally disposed bolts and should the openings for these bolts be unevenly positioned, or from various other causes, the cushions will not be arranged at a uniform height above the top surface of the table bed 12. This is overcome in the present invention by extending bolts 18 downwardly through the rails, the bed and frame and by means of these bolts proper adjustment may be made to effect a uniform height of the cushions. This is desirable in a billiard table especially where a player "goes to the bank" or cushion during a play, as the effect upon the ball will be the same irrespective of where the ball strikes the cushion. Another advantage of securing the rails in the manner shown resides in the fact that when the rails are removed or adjusted the finish of the table will not be marred.

The corner pockets which are indicated at 19 and the side pockets indicated at 20 are open at the bottom and extending along the opposite sides of the table below and communicating with the pockets 19 and 20 are inclined runways or channels 21, the said runways or channels being formed in members 22 secured to the table frame. The bottoms of these runways are provided with spaced preferably rubber strips 23 which provide tracks upon which the balls 24 will run after leaving the pockets so that noise ordinarily present during the return of the balls is eliminated and damage to the balls prevented.

The side runways 21 are connected at their lower ends by a transverse runway or channel 25, the latter being also formed in a member 26 located beneath and within the margin of the table. Thus, no projecting surfaces or corners are present which might interfere with the comfort of the player, or

which might become loosened or damaged due to the tendency of the players resting their feet upon the boxes usually employed for collecting the returned balls. In the present invention the balls are collected in the runway 25 and the latter is provided with an elongated opening 27 in one wall thereof through which the balls may be removed.

The pockets 19 and 20 extend downwardly through the rails 14 and the latter are relatively wide and form rear and side walls for the pocket entrances so that the necessity of employing the usual irons in the formation of the pockets is obviated. This reduces danger of the balls bouncing from the pockets, which danger is further reduced by the upwardly and inwardly curved walls 28 of the pockets, the said walls being located remote from the pocket entrances so as to direct the balls downwardly within the pockets and eliminate objectionable rebounding after a ball once enters a pocket. Located within the runways or channels beneath the pockets are cushions 29, preferably constructed of leather.

The invention is susceptible of various changes in its form, proportions and minor details of construction and the right is herein reserved to make such changes as properly fall within the scope of the appended claims.

Having described the invention what is claimed is:—

In a pocket billiard table, side and corner pockets open at the bottom, longitudinally disposed inclined channeled members secured to the bottom of the table upon each side thereof beneath the pockets and a channeled member secured transversely beneath and within the marginal edge of one end of the table and having its opposite ends in communication with the lower ends of the side channeled members and said transversely channeled member having an opening in one side thereof.

In testimony whereof we affix our signatures.

GIOVANNI CORREALE.
ERNEST CORREALE.
